UNITED STATES PATENT OFFICE

105,216

DESIGN FOR A CONNECTER PLUG

William P. Herman, Providence, R. I.

Application April 17, 1937, Serial No. 68,847

Term of patent 14 years

To all whom it may concern:

Be it known that I, William P. Herman, a citizen of the United States and resident of Providence, in the county of Providence and State of Rhode Island, have invented a new, original, and ornamental Design for Connecter Plug, of which the following is a specification, reference being had to the accompanying drawing, forming part thereof.

In the drawing:

Fig. 1 represents a plan view of the novel connecter plug;

Fig. 2 is a side view thereof; and

Fig. 3 is a bottom view thereof.

Both sides of the connecter plug are ornamented as shown in Fig. 2.

I claim:

The ornamental design for a connecter plug, as shown and described.

WILLIAM P. HERMAN.
